US0D1052358S

(12) **United States Design Patent** (10) **Patent No.:** **US D1,052,358 S**
(45) **Date of Patent:** **** Nov. 26, 2024**

(54) **JUICER MOTOR HOUSING**

(71) Applicant: **SharkNinja Operating LLC**,
Needham, MA (US)

(72) Inventor: **Trevor Dyment**, Boston, MA (US)

(73) Assignee: **SharkNinja Operating LLC**,
Needham, MA (US)

(**) Term: **15 Years**

(21) Appl. No.: **29/884,402**

(22) Filed: **Feb. 10, 2023**

(51) **LOC (14) Cl.** **31-00**

(52) **U.S. Cl.**

USPC **D7/665**

(57) **CLAIM**

The ornamental design for a juicer motor housing, as shown and described.

DESCRIPTION

FIG. 1 is a right side/top perspective view of a juicer motor housing in accordance with the subject technology.

FIG. 2 is a mirrored left side/top perspective view of the juicer motor housing of FIG. 1 in accordance with the subject technology.

FIG. 3 is a left side view of the juicer motor housing of FIG. 1.

FIG. 4 is a right side view of the juicer motor housing of FIG. 1.

FIG. 5 is a front view of the juicer motor housing of FIG. 1.

FIG. 6 is a back view of the juicer motor housing of FIG. 1.

FIG. 7 is a top view of the juicer motor housing of FIG. 1; and,

FIG. 8 is a bottom view of the juicer motor housing of FIG. 1.

The purpose of the broken lines shown in the drawings is to denote features of the structure that form no part of the claimed design.

1 Claim, 6 Drawing Sheets
